Primary Examiner — Derrick E Holland*Assistant Examiner* — Andrew Kerr(74) *Attorney, Agent, or Firm* — Kenja IP Law PC(57) **CLAIM**

The ornamental design for a foldable solar panel, as shown and described.

DESCRIPTION

FIG. 1 is a perspective view of a foldable solar panel showing our new design;

FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a bottom view thereof; and,

FIG. 8 is an enlarged sectional view taken along line **8-8** in FIG. 2.

The dash-dash broken lines showing portions of the foldable solar panel are for the purpose of illustrating environmental structure and form no part of the claimed design. The dot-dash broken lines represent the boundary of the claimed design and form no part of the claimed design.
